FIG. 2.

INVENTOR
O. O. LEWIS

by W. J. Fitz Gerald & Co.

ATTORNEY

UNITED STATES PATENT OFFICE.

ORVILLE O. LEWIS, OF COLDWATER, KANSAS.

TREMOLO.

1,426,749.

Specification of Letters Patent. Patented Aug. 22, 1922.

Application filed June 23, 1921. Serial No. 479,860.

To all whom it may concern:

Be it known that I, ORVILLE O. LEWIS, a citizen of the United States, residing at Coldwater, in the county of Comanche and 5 State of Kansas, have invented certain new and useful Improvements in Tremolos; and I do hereby declare the following to be a full, clear, and exact description of the invention, such as will enable others skilled 10 in the art to which it appertains to make and use the same.

The present invention relates to sound modifying accessories or attachments for stringed instruments, and aims to provide a 15 device attachable to a violin, violo, cello or other stringed instruments for creating a tremulous tone, and for want of a more appropriate name, the device has been denominated a tremolo.

20 Another object is the provision of such a device which is novel in construction, and readily attachable to a violin or other stringed instrument, for producing an effective tremulous tone or music when the 25 instrument is played in the customary manner.

It is also an object of the invention to provide such a device which is also simple and inexpensive in construction, and which 30 can be made to modify the tremulous effect in different ways.

With the foregoing and other objects in view, which will be understood as the description proceeds, the invention resides in 35 the construction and arrangement of parts hereinafter described and claimed, it being understood that changes can be made within the scope of what is claimed without departing from the spirit of the invention.

40 The invention is illustrated in the accompanying drawing, wherein:—

Figure 1 is a side elevation of the device as applied to the bridge of a violin or similar stringed instrument.

45 Fig. 2 is a face view thereof.

Fig. 3 is an enlarged section on the line 3—3 of Fig. 2.

Fig. 4 is a sectional view showing a modified form.

50 In carrying out the invention, there is provided a box 6 of suitable size and shape, and of sheet metal or other appropriate material, and having the cap 7 soldered or otherwise fastened thereon. As shown, the 55 box has opposite disk heads or sides, and is of circular form.

The box 6 is secured at its periphery to the free end of a leaf spring 8, with the sides or heads of the box in planes substantially parallel with said spring, whereby the box 60 will vibrate substantially axially thereof with the spring. The basal terminal of the spring overlaps and is secured to a U-shaped clip 9, which is resilient to fit over and frictionally grip the bridge 10 of a violin, violo, 65 cello or other stringed instrument, to fasten the spring to the bridge for vibration therewith, with the spring 8 and box 7 in substantially the same plane as the bridge, so that the box can vibrate forwardly and 70 rearwardly transversely of the plane of said bridge.

A vibratory spring tongue 11 of suitable sheet metal or other resilient material is disposed within the box substantially diametrically thereof, and is of tapered form, as shown, with its wider end free within the box and its narrower end rigidly secured to the periphery of the box, at as 12, by means of solder or the like. The tongue or vibratory member 11 thus extends from the periphery of the box and intersects the axis of said box, and said tongue can vibrate between the sides or heads of the box in substantially the same direction as the spring 8. 85 One side or head of the box has a central aperture 13, across which the tongue extends on the inside of the box.

When the clip 9 is engaged over the upper edge of the bridge 10 of a violin or other stringed instrument for which the device is suitable, the vibrations of the bridge, when playing the instrument, are transmitted by the spring 8 to the box 6, which in vibrating will impart vibrations to the 90 tongue or reed 11. Air waves are therefore set up within the box, and through the aperture 13, which will render the music of 95 pleasing and effective tremulous quality. By using boxes of different sizes, apertures 13 of different sizes, and tongues of different material and sizes, the quality of tremulous tones can be varied. Also, as suggested in Fig. 4, a number of vibrating tongues can be used within the box. Thus, 100 as shown, an additional tongue 11' is secured to the periphery of the box and crosses the tongue 11, whereby both tongues can vibrate, and they may be of different pitches.

Having thus described the invention, 110 what is claimed as new is:—

1. A device of the kind described compris-

ing freely vibratory means to engage a vibratory portion of a stringed instrument, and vibratory sound-modifying means supported from said means for free vibration 5 and also having a vibratory portion within itself vibratory relatively to the first named means.

2. A device of the character described comprising a spring having means for attachment to a vibratory portion of a stringed instrument for the free vibration 10 of said spring, and vibratory sound-modifying means supported by said spring for free vibration therewith and having a vibratory 15 portion within itself to vibrate relatively to the spring.

3. A device of the kind described comprising a clip to engage a vibratory portion of a stringed instrument, a spring supported 20 by the clip for free vibration, and vibratory sound-modifying means carried by the free portion of said spring for free vibration with the spring and having a vibratory 25 portion within itself vibratory with reference to the spring.

4. A device of the kind described comprising a leaf spring for attachment to a vibratory portion of a stringed instrument to vibrate freely, and vibratory sound-modifying means supported by the free portion 30 of the spring and having a freely vibratory portion within itself adapted to vibrate relatively to the spring.

5. A device of the kind described comprising a clip to fit a vibratory portion of a stringed instrument, a leaf spring secured to and extending from the clip for free vibration, and a vibratory sound-modifying member supported by the free portion 40 of said spring for free vibration with the spring and having a vibratory portion within itself adapted to vibrate relatively to the spring.

6. A device of the character described comprising a hollow box having an aperture, means for supporting said box from a vibratory portion of a stringed instrument for

the free vibration of said box, and a vibratory member in said box to create sound waves through said aperture by the vibration of said instrument. 50

7. A device of the kind described comprising a hollow box having an aperture, means for supporting said box from a vibratory portion of a stringed instrument 55 for the free vibration of said box, and a vibratory tongue mounted in said box to vibrate relatively to the box.

8. A device of the kind described comprising a hollow box having an aperture in 60 one side, means for supporting said box from a vibratory portion of a stringed instrument for the free vibration of said box, and a tapered vibratory tongue within the box extending across said aperture and having its smaller end secured to the box. 65

9. A device of the kind described comprising a spring to be supported from a stringed instrument, a hollow box supported by said spring for free vibration with the 70 spring, and a vibratory member in said box for modifying the tones of said instrument.

10. A device of the kind described comprising a spring to be supported by a vibratory portion of a stringed instrument, 75 a hollow box supported by said spring for free vibration with the spring and having an aperture, and a vibratory member in said box for creating sound waves through said aperture. 80

11. A device of the kind described comprising a clip to fit on the bridge of a stringed instrument, a leaf spring secured to and extending from said clip, a box supported by said spring and having an aperture, and a vibratory tongue mounted in 85 said box and extending across said aperture.

In testimony whereof I have signed my name to this specification in the presence of two subscribing witnesses.
